UNITED STATES PATENT OFFICE.

GEORGE N. CLARK, OF NEEDHAM HEIGHTS, MASSACHUSETTS, ASSIGNOR TO CENTRAL RAILWAY SIGNAL COMPANY, OF PITTSBURGH, PENNSYLVANIA, A CORPORATION OF NEW JERSEY.

FUSEE-TUBE-FILLING MACHINE.

1,267,183.

Specification of Letters Patent.

Patented May 21, 1918.

Application filed September 12, 1917. Serial No. 191,047.

To all whom it may concern:

Be it known that I, GEORGE N. CLARK, a citizen of the United States, residing at Needham Heights, in the county of Norfolk and State of Massachusetts, have invented certain new and useful Improvements in Fusee-Tube-Filling Machines, of which the following is a specification, reference being had therein to the accompanying drawing.

10 This invention relates to improvements in fusee tube filling machines, and pertains to a machine constructed to receive a plurality of fusee tubes to be filled with a burning chemical.

15 The fusees which this machine is especially adapted to fill is of the railway signal type, and they are constructed to burn predetermined periods of time, so that when either thrown upon or left upon a railway 20 track or right of way, a following train will be signaled by this burning fusee.

These railway signal fusees are also adapted to burn different colors; some red, some yellow, some green, etc., and some are 25 what are known as combination railway signal fusees in that they burn one color for a certain period of time and a different color for the remainder of its period of burning. All of these different colors and 30 combination of colors have certain meanings to the railroad engineers, and indicate to them how long since the train ahead has passed, and the following train is run accordingly.

35 In constructing these railway signal fusees, it is necessary to pack the burning chemical therein substantially uniformly throughout the length of the paper fusee tube, in order to get uniform burning and reliable burning 40 for a predetermined time. In addition to these fusees burning different colors, they burn predetermined periods of time. The majority of them are regulated to burn five or ten minutes and are known and designated respectively as five and ten minute 45 fusees, either red, green or yellow—as the case may be. The railroads require, and the signaling systems demand that a five minute fusee must burn substantially five minutes 50 and substantially no longer. In order to

meet this time burning requirement, it is necessary (as above stated) that the burning chemical be packed in the paper tubes substantially uniformly throughout. In order to do this, the chemical is supplied 55 to these tubes in several measured charges for each fusee, and each charge is packed therein before the next charge is fed to the tube, and each charge is subjected to the same packing blows by the packing rods. 60

One object of my present invention is to provide means for stopping and starting the packing action, thus giving time to place a battery of tubes in the tube-rack and the filling board in position over the 65 open upper ends of the tubes, and sometimes, when necessity requires it, stop the packing action while the charging board is placed within and removed from the machine, though usually skilled operators are able to 70 place the charge board within the machine and discharge it and remove it therefrom, when the packing rods are withdrawn.

Another object of my invention is to provide improved charging boards for charging 75 the tubes.

In the accompanying drawings—

Figure 1 is a front elevation of a fusee tube filling machine which embodies my invention.

Fig. 2 is an edge elevation of the same, showing the packing element or carrier stopped.

Fig. 3 is a sectional view on the line 3—3 of Fig. 1, looking in the direction indicated 85 by arrow.

Fig. 4 is an edge elevation, the upper end in section with the parts in position to permit the operation of the packing element or rod carrier.

Fig. 5 is a plan view of a part of that form of filling board that is used for the one color fusee.

Fig. 6 is a sectional view of Fig. 5.

Fig. 7 is a plan view of a filling board 95 used for a combination color fusee.

Fig. 8 is a sectional plan view showing the zigzag movement of the movable member of the board.

Referring now to the drawings, the ma- 100

chine consists of a framework made up of side pieces 1, connected at their tops by a cross-piece 2. The upper portions of the side pieces 1 are bifurcated to form the 5 parallel arms 3, between which a packing rod head or member 4 moves up and down, the said member 4, having reduced ends 5 fitting between the arms 3, thus serving to guide the packing rod or head 4 in its 10 up and down movements. This packing head 4 is provided with a plurality of packing rods 6, which have their upper ends beaded as at 7, and they fit loosely in vertical openings 8 formed in the head 4, so that the 15 head or carrier 4 may move up and down independent of the packing rods 6, when the carrier 4 is down and the lower ends of the packing rods are in engagement with the material in the fusee tubes.

20 An operating shaft 9 is suitably journaled at the upper part of the frame of the machine and is driven by a suitable pulley 10 from any desired source. During the operation of the machine, the shaft 9 continuously revolves. Each end of the shaft 9 is provided with a crank-arm 11, and the free end of the crank arm is provided with a wrist pin 12, slidably fitting within the slots 13 of a slotted link 14. The slots 13 are of 25 a length equal to the diameter of the circle described by the crank arms 11. The lower ends of the links 14 are pivotally connected with the extensions 5 of the rod or carrier 4 at the points 15.

30 A latch 16 of bell-crank shape is intermediately pivoted at 17 and so located that its short end 18 may be caused to drop in the line of travel of one of the ends 5 of the rod carrier 4, as shown in Fig. 2, and 35 support the carrier 4 in its uppermost position. Preferably at the point of engagement of the latch with the end 5 a metallic plate 19 is placed on the end 5, to take the wear of the latch. When the latch and carrier 4 are in the position shown in Fig. 2, the carrier is held against up and down movement and the shaft 9 continuing to revolve, its wrist-pin 12 simply travels back and forth in the slot 13 of the link 14.

40 When it is desired to release the rod packing head to permit it to travel up and down, the operator presses on the treadle 20, pulling down on a rod 21 which has its upper end connected with the outer end of a bell-crank 22, the other end of the bell-crank 22 being connected with the outer free end 55 of a lever 23, at the point 24. This lever 23 is independently pivoted at the point 25 on a vertically arranged block 26. The ends 60 of this block 26 are provided with vertical pivots 27 in a U-shaped bracket 28, so that the lever 23 has up and down movement on the block 26, and a lateral movement by turning the block to which it is pivoted.

The inner free end 29 of the lever 23 is provided with a roller 30 adapted to be engaged by a cam 31, on the operating shaft 9 when the treadle 20 is depressed and the inner free end of the lever 23 is caused to swing into the path of travel of the cam 31, as 65 shown in Fig. 4. The cam 31 is positioned in substantially the same radius as the crank arms 11, so that when the crank arms are up, the lever 23 is turned on its pivot forcing its outer end downward. The outer end of the 70 lever 23 being connected with the outer arm of the lever 16 by a link 32, it in turn depresses the outer end of the latch 16, thus withdrawing its inner end out of the path of the end 5 of the packing rod, head or carrier 4.

75 There is a latch 16 for each of the ends 5 of the rod carrier 4, and the outer ends 33 of the latches are connected by a rod 34. A spring 35 has its lower end connected with the rod 34, and its upper end connected with a member 36, carried by the top piece 2, which spring is normally contracting and normally pulling upward on the rod 34, and normally tending to throw the inner ends 36 80 of the latches 16 in the path of travel of the ends 5 of the rod or carrier head 4.

85 For the purpose of locking the latches 16 in their inoperative positions, shown in Fig. 4, I provide a locking latch 37 pivoted at 90 the point 38 to one of the arms 3. This locking latch 37 is provided with a weighted arm 39, normally holding the lower edge of the latch 37 over the long arm 33 of the latch 16, as shown in Fig. 4, and locking it 95 in its inoperative position. Therefore, when the treadle 20 is depressed and through the mechanism described, the cam 31 is caused to engage the roller 30 and operates the lever 23 to depress the latch 16 in the position shown in Fig. 4, the locking latch 37 falls over the latch 16 and locks it in its inoperative position, thus permitting the packing rod carrier 4 to be moved up and down. When it is desired to stop the up and down 100 movement of the packing rod carrier 4, the operator depresses the treadle 40, which is connected by a rod 41, with the lower end of the bell-crank lever 42, the upper end 105 of the lever 43 will throw the latch 37 inward and release the latches 16. When the rod carrier 4 moves upward, it moves the ends 36 of the latches 16 outward and they 110 immediately fall inward holding the rod carrier 4 in its upper position.

115 It is necessary to stop the packing rod carrier 4 when the fusee tubes 44 are placed in the tube rack 45, and while the filling board 46 is placed in the position shown in Fig. 3. This filling board has cavities 47 120 in its under side to receive the upper ends of the fusee tubes 44 and communicating with these recesses are tapered passages 48.

Also shown in Fig. 3 is the charging board 49, which has a plurality of pockets or passages 50, corresponding in number to the passages 48 of the filling board. This charging board also has a sliding shutter secured at its bottom, which also has openings 52 corresponding to the pockets 50 of the filling board. In the position shown in Fig. 3, the shutter 51 is closing the pockets of the filling board. The operator fills the board while it is in the machine, and then in the act of pushing the filling board in position, the projecting end 53 of the shutter 51 engages the stop 54 so that by continuing to push in the charging board 49, the pockets 50 are brought in line with the openings 52 of the shutter, and the chemical falls into the passage 48 and into the fusee tubes 44. The charging board is then immediately removed and the packing operation by the rods 6 comes into action. These rods 6 pass down into the fusee tubes and pack the chemical therein, each charge being packed after it is fed into the tubes.

In order to have the filling machine receive a large number of tubes, they are placed close together, in fact, closer together than the diameter of the tubes. Owing to this arrangement in the form of charging board 55, shown in Fig. 5, the openings or pockets 50 are not entirely closed, but as this board is used for a one-color fusee, it is not important that the charges be uniform, and the falling of some of the chemical through the partially open passages is not important. For this reason the filling board 55 has its shutter 56 moved in a straight line.

But when the combination is being used, in which two or more kinds of chemicals are placed in the same tube to produce different colors, each color must burn its specified time and it is necessary in this event to have accurate charges for the different colors. For instance, the first color must have a certain number of charges to give the desired result, and there must not be any overcharge, as would happen were the openings or pockets not entirely closed while the board is being filled. In order to insure the complete closing of the pockets 50, as shown in Fig. 3, the shutter 51 has zigzag movement, that is an inward and lateral movement by reason of the inclines 57. By this construction when the shutter is placed in a closing position, its openings 52 are to one side of the pockets, literally speaking, and in that way the pockets are completely closed, as shown in Fig. 3. When the board 49 is pushed inward, it and the shutter have relative inward and lateral movements which bring the openings 52 in a line under the pockets 50 and permit them to empty. By this inward and lateral movement of the shutter, the pockets 50 are com-

pletely closed when the board is being filled, 65 and there can be no surplus chemical fed through the charging board, therefore insuring accurately measured charges each time the board is filled and emptied, and insuring accurate measurements for the different colored charges placed in the fusee tube. It will, of course, be understood that the colored charges in the tube may be composed of one or more, and usually more than one filling board charge, but in this way the accuracy is insured in the amounts fed to the tubes for their different colored charges. 75

Having thus described my invention what I claim and desire to secure by Letters Patent is:—

1. A fusee tube filling machine comprising a tube carrier, a reciprocating packing rod carrier, an operating mechanism for reciprocating the rod carrier, a locking member for holding the carrier out of operation, a power actuated device connected with the locking member, and a foot mechanism adapted to control the power actuated mechanism. 80

2. A fusee tube filling machine comprising a tube holder, a vertically reciprocating packing rod carrier, a driving shaft operatively connected with the rod carrier, a locking member for holding the rod carrier out of operation, a driving shaft having a cam actuated mechanism between the locking member and the cam, and means for controlling the actuated mechanism. 90

3. A fusee tube filling machine comprising a tube holder, a vertically reciprocating packing rod carrier, a driving shaft connected and adapted to reciprocate the carrier, a locking member for locking the carrier out of operation, a cam on the driving shaft, a laterally and vertically swinging lever adapted to have one end moved in the path of the cam, the other end of the lever operatively connected with the locking member and means for swinging the lever laterally to cause the cam through the lever to release the locking member. 100

4. A fusee tube filling machine comprising a tube holder, a vertically reciprocating packing rod carrier, a driving shaft having a crank arm, a link connection between the crank arm and the rod carrier, the link having a slot of a length equal to the diameter of the circle described by the crank arm, the crank arm having sliding connection with the slot in the ring, a locking member for locking the rod carrier out of operation, a driving shaft having a cam in substantially the same radius of the crank arm, a laterally movable lever having one end adapted to coöperate with the cam, and the other end operatively connected with the locking member, and means for swinging the lever laterally. 115

5. A charging board for fusee tubes, comprising a main body portion, having vertically arranged charging pockets with open ends, said charging pockets being closer together than the diameter of the pockets, a longitudinally and laterally movable shutter at the bottom of the filling board, the shutter having openings corresponding with the

openings in the board, whereby the longitudinal and lateral movement of the shutter ¹⁰ will completely close and completely open the charging pockets.

In testimony whereof I hereunto affix my signature.

GEORGE N. CLARK.
